(73) Assignee: **Harman International Industries, Incorporated**, Northridge, CA (US)

(57) **CLAIM**

(**) Term: **14 Years**

The ornamental design for a radiation boundary integrator for a loudspeaker system, as shown and described.

(21) Appl. No.: **29/127,145**

DESCRIPTION

(22) Filed: **Jul. 31, 2000**

FIG. 1 is a front perspective view of a radiation boundary integrator for a loudspeaker system showing my new design;

(51) LOC (7) Cl. **14-01**

FIG. 2 is a front elevational view thereof;

(52) U.S. Cl. **D21/221**

FIG. 3 is a right elevational view thereof;

(58) Field of Search **D10/46; D21/221,**

FIG. 4 is a left elevational view thereof;

D21/214; 181/144, 145, 147, 155, 156,
152, 159, 187, 199, 192; 381/339, 340,
342, 188, 205, 87, 88-90, 182, 156

FIG. 5 is a bottom plan view thereof;

(56) References Cited

FIG. 6 is a rear elevational view thereof;

U.S. PATENT DOCUMENTS

FIG. 7 is a cross-sectional view along line 7—7 in FIG. 6;

D. 379,355 * 5/1997 Larson et al. **D14/221**
5,590,214 12/1996 Nakamura .

and,

FIG. 8 is a cross-sectional view along line 8—8 in FIG. 6.

The dotted line showing of the enclosure in FIG. 1 is for environmental purposes and from no part of the claimed design.
